UNITED STATES PATENT OFFICE.

DAVID L. WINTERS, OF LOS ANGELES, CALIFORNIA.

ATTACHMENT FOR SPARK PLUGS.

Application filed April 12, 1926. Serial No. 101,491.

My invention relates generally to spark plugs as used for igniting a charge of fuel in the cylinders of an internal combustion engine, and a purpose of my invention is the provision of a simply constructed durable and inexpensive attachment for spark plugs which is primarily intended to replace the usual grounded point of the plug.

In the conventional spark plug, it is the general practice to fixedly secure the grounded point to the inner end of the shell and this point is usually constructed from a short length of wire bent into substantially L-shaped form with one end spaced from the central or insulated point to provide the necessary spark gap. This construction has many outstanding disadvantages, among which are that it does not readily free itself from oil, hence permitting the accumulation of carbon; the correct amount of gap between the points is not maintained, as the eroding effect of the spark is confined to an exceedingly small area; does not ignite a sufficient amount of the fuel charge to promote complete combustion and is not readily replaced when erosion thereof has rendered it unfit for further use.

My invention entirely eliminates the disadvantages above set forth, is easily attached to a plug and delivers a uniform spark regardless of engine temperature, to thus provide a thoroughly reliable and efficient spark plug. Another purpose of my invention is the provision of a device of the above character which is so constructed that the spark gap is automatically increased or decreased accordingly as the temperature of the engine increases or decreases, this construction permitting the points to be initially adjusted very close to facilitate easy starting of the engine when the voltage of the battery during turning over of the engine is too low to jump a wider gap, and at the same time ignite a greater portion of the fuel charge than is possible with the conventional points.

I will describe only two forms of attachments for spark plugs and will then point out the novel features thereof in claims.

In the accompanying drawings:

Figure 1 is a view showing partly in side elevation and partly in section a conventional spark plug with one form of attachment embodying my invention in applied position thereto;

Figure 2 is a plan view of the inner end of the plug with the attachment shown in the preceding view;

Figure 3 is a perspective view of the attachment;

Figure 4 is a fragmentary vertical sectional view of the inner end of a spark plug with a modified form of my invention applied thereto; and

Figure 5 is a view similar to Figure 2, but showing the modified form of my invention.

Referring specifically to the drawings, in which similar reference characters designate similar parts in each of the several views, and more particularly to Figures 1 to 3, inclusive, my invention is shown as comprising an element designated generally at E which in the present instance is formed from a single sheet of bendable and slightly resilient metal to provide a split sleeve or cylinder 10 with its diameter slightly greater than the diameter of the pocket 11 formed in the inner end of the shell 12 of a conventional spark plug S. Adjacent one end the sleeve 10 is slit transversely from its open side, as indicated at 13, to provide a pair of tongues T and T', which are adapted to function as the grounded points of a plug. The tongues are bent outwardly from each other beyond the diameter of the inner end of the sleeve, to provide shoulders at the outer side of the latter, as clearly shown at 14 in Figure 2, while their free ends are curled inwardly towards each other as at 15 and beveled at 16, so as to provide a pair of knife edged points arranged in spaced relation.

In the application of my attachment to the spark plug S, the conventional grounded point 17 of the plug is bent outwardly a sufficient distance to permit one end of the sleeve 10 after being slightly contracted from its normal position to be inserted into the pocket 11. The sleeve is now pushed into the pocket until the tongues T and T' engage the inner end of the shell 12, in which position the tongues will be disposed opposite the usual central or insulated point 18 which extends through the conventional porcelain sleeve 19 and projects beyond the inner end of the shell. It will be clear that under its expansive action the sleeve is frictionally held against movement in the pocket 11 and should it be desired to positively secure the sleeve to the shell the conventional grounded point

17 may be utilized by cutting off a portion thereof and bending its free end over the inner end of the sleeve, thus positively preventing the displacement of the latter. The free ends of the tongues T and T' may now be adjusted with respect to the central point 18 to provide the necessary spark gap and it will be noted that due to their curved form they will be affected by the temperature of the engine to the extent that they will expand upon an increase in temperature and move outwardly or away from each other and from the central point 18 so as to increase the spark gap, while upon a decrease in temperature the tongues contract and close to the point 18 so as to reduce the spark gap. The advantage of a variable spark gap dependent upon the heat of the engine will be readily apparent when it is understood that upon initially adjusting the spark gap it can be made less than is the usual practice so as to facilitate starting of the engine when the voltage of the battery during turning over of the engine is low, and that as the engine heats up the gap will automatically increase, thus conforming to the needs of the engine when running. Furthermore, due to the vertical position of the tongues with respect to the plug, any undue accumulation of oil readily drips off, while because of the fact that they are comparatively free from the water cooled portion of the engine at the inner end of the plug, they become sufficiently heated to cause any film of oil that may adhere to them to be burned off.

It will be understood when it is considered that the element E is formed from a flat sheet of metal, that upon bending the tongues T and T' into the curved shape shown in Figure 2, the metal at the inner side of a medial line drawn longitudinally through the thickness of the tongues will be slightly compressed while that to the outer side will be slightly stretched. Because of this fact it will be readily apparent that with the tongues adjusted relatively close to the central point 18 so as to facilitate easy starting of the engine under low battery voltage, the increase in temperature as the engine warms up will expand the tongues, and to a greater extent at the inner sides of the tongues than at the outer, due to the compressed or denser state of the metal at the inner sides. The tongues will thus tend to straighten out and thereby increase the spark gap, and while this movement of the tongues is relatively small, it is nevertheless sufficient to effect the necessary increase so that a fat spark of maximum heat intensity will be obtained for operating the engine. Accordingly as the temperature decreases the tongues will tend to assume the shape to which they were originally bent to thereby decrease the spark gap. It will thus be clear that the tongues function automatically in response to variations in temperature

to vary the spark gap so that the desired fat spark will be obtained under all operative conditions.

In addition, it will be clear that the tongues also confine and materially preheat the portion of the fuel charge to be ignited, thus greatly accelerating the progress of combustion under all conditions of operation, and especially during the "pick up" when the mixture is poor and there is more time available for this purpose.

Referring to Figures 4 and 5, I have herein shown a modified form of attachment to be used in engines wherein it is not desired to preheat the portion of the charge to be ignited. In this form, the attachment comprises a split sleeve 20 provided with a depending extension 21 at a point opposite to its open side, the free end of the extension being curled as at 22 to clampingly engage a short length of wire 23 having its ends curled inwardly towards each other and arranged in spaced relation, as is clearly shown at 24 in Figure 5.

In the application of the sleeve 20 to the plug, its larger end is contracted and the sleeve forced into the pocket 11 until its smaller end is substantially flush with the inner end of the shell 12, in which position the wire 23 will be arranged with its curled ends 24 disposed at opposite sides of the central point 18. The curled ends are now adjusted with respect to the central point 18 to provide the required spark gap and respond to changes in temperature in the same manner as the tongues T and T'. If desirable, the wire 23 may be welded to the sleeve 20.

The conventional grounded point 17 may be utilized to positively prevent displacement of the sleeve 20 by bending its free end over the end of the extension 20, and in the event that the point has been broken off the inner wall of the shell can be upset at one or more points by a suitable tool (not shown) to engage the sleeve and prevent its displacement.

By reference to Figures 2 and 5, it will be clear that by the provision of the split sleeves 10 and 20, they are capable of being constricted or expanded to accommodate different diameters of the pockets 11, so that the attachment can be readily applied to plugs of respectively different sizes and types to snugly fit within the pockets thereof.

Although I have herein shown and described only two forms of attachment for spark plugs embodying my invention, it is to be understood that various changes and modifications may be made therein without departing from the spirit of my invention and the spirit and scope of the appended claims.

I claim as my invention:

1. An attachment for spark plugs comprising a sleeve split longitudinally and slit transversely from its open side adjacent one

end to provide a pair of tongues, said tongues being curved outwardly from each other to provide shoulders at the outer side of the sleeve and having their free ends curled inwardly towards each other so as to be arranged in spaced confronting relation.

5. 2. As an article of manufacture, an attachment for spark plugs formed from a single sheet of bendable metal to provide a sleeve 10 split longitudinally throughout its length and slit transversely from its open side adjacent one of its ends to provide a pair of companion tongues, said tongues extending transversely of said sleeve and curved outwardly from 15 each other with their free ends curled inwardly towards each other and arranged in spaced relation.

3. An attachment for spark plugs comprising a sleeve split longitudinally and provided 20 with an extension at one end disposed oppositely to its open side, means adapted to constitute the ground point of the plug comprising a single length of wire bent into C-shaped form, the free end of said extension 25 being curled to clampingly engage and support said wire intermediate its ends in a position substantially transversely of the length of the sleeve.

4. An attachment for spark plugs comprising 30 a sleeve split longitudinally, and a single length of wire in the form of a C secured to the sleeve so as to extend transversely of one end thereof.

5. An attachment for spark plugs comprising 35 a tubular element adapted to be inserted into the shell of the plug for electrical connection with the shell, and a tongue on the member shaped to move laterally and in a

plane transversely of the length of the tubular element in response to changes in temperature.

6. An attachment for spark plugs comprising 40 a sleeve adapted to be inserted into the shell of a spark plug, the sleeve being split longitudinally and slit transversely from its open side adjacent one end to provide a tongue, the tongue being curved outwardly to project beyond the outside diameter of the sleeve to thereby provide a shoulder adapted to engage the end of the spark plug shell so as to definitely limit the position of the sleeve 45 inwardly of the shell, the free end of the tongue being curved inwardly.

7. An attachment for spark plugs as embodied in claim 6 wherein the sleeve, when 50 inserted into the spark plug shell with said shoulder engaging the end of the shell, has its outer end so positioned with respect to a bendable electrode on the shell, that the electrode is adapted to be bent over the outer end 55 of the sleeve to thus co-operate with said shoulder in positively securing the sleeve against displacement from the shell.

8. An attachment for spark plugs comprising 60 a tubular element capable of being inserted into the shell of the plug and having an electrode thereon adapted to co-act with an electrode on the plug to form a spark gap, the tubular element, when inserted into the shell 65 of the plug, having its outer end so positioned with respect to a bendable electrode on the plug that the electrode is adapted to be bent over the outer end of the element to thus positively secure the latter against outward displacement from the shell.

DAVID L. WINTERS.
